(57) **CLAIM**

The ornamental design for a brush plug, as shown and described.

DESCRIPTION

FIG. 1 is a front perspective view of a brush plug in accordance with the present design;

FIG. 2 is a bottom perspective view thereof;

FIG. 3 is a right side elevational view thereof;

FIG. 4 is a left side elevational view thereof;

FIG. 5 is a rear elevational view thereof;

FIG. 6 is a front elevational view thereof;

FIG. 7 is a top plan view thereof; and,

FIG. 8 is a bottom plan view thereof.

The broken lines shown in the drawings illustrate portions of the brush plug that form no part of the claimed design.

1 Claim, 4 Drawing Sheets
